UNITED STATES PATENT OFFICE.

JOHN P. WEIS, OF NYACK, NEW YORK, ASSIGNOR TO METROPOLITAN SEWING MACHINE CORPORATION, OF NYACK, NEW YORK, A CORPORATION OF DELAWARE.

SEWING MACHINE.

Application filed March 29, 1921. Serial No. 456,729.

To all whom it may concern:

Be it known that I, JOHN P. WEIS, a citizen of the United States, residing at Nyack, in the county of Rockland and State of 5 New York, have invented certain new and useful Improvements in Sewing Machines, of which the following is a specification.

This invention relates to sewing machines, an object thereof being to provide an improved mechanism for laying a thread on top of the work in alternating loop form, such loops being stitched down on top of the work by the needle threads for the purpose of making an ornamental or cover 10 seam for joining pieces of goods. This invention is particularly useful when used in conjunction with a complementary stitch-forming mechanism, such as a transverse thread carrying looper which forms ornamental or covering stitches on the bottom of the work by the concatenation of the looper thread with the needle threads.

A further object of this invention is to provide an improved mechanism for laying 15 across the path of the needles loops of thread to be stitched down by the needle threads, the improved construction being such that the operating mechanism is entirely out of the way so as not to interfere 20 with the hands of the operator, during the handling of the work.

A further object of the invention is to provide a thread loop-forming mechanism 25 capable of very high speeds, free from noise and vibration, efficient and economical in operation, and of such construction as to necessitate a minimum of care, adjustment, replacement and oiling.

A further object of this invention is to 30 provide an improved mechanism for laying a cross-thread, such mechanism having but one movement, namely, a continuous motion in one direction and comprising such improved instrumentalities as to render the 35 same simple to thread, and capable of laying a thread in uniform alternating loops in the path of the needles irrespective of the length of stitches.

A further object of the invention is to 40 provide a rotary loop former carried by the presser foot of the sewing machine, capable of laying in alternating loop form 45 in the path of the needles the thread to be stitched down by the needle threads, the

driving means for the thread loop-forming 55 mechanism being derived from the rotary top shaft of the sewing machine.

One of the advantages of the present invention is that the mechanism combines simplicity with efficacy, consists of a minimum of parts, and is adapted to give a continuous rotary motion to the thread loop former which carries a loop of thread into position in the path of the needles, the rotary motion of the thread loop-former being 60 continuous in the presser foot of the sewing machine, and the center of the thread loop-former being alined with the vertical axis of the needle bar. Thus, my improved mechanism is capable of co-operation with 65 needles of different gauges for the purpose of making different widths of seams, the thread loop-former being carried by a ring gear in the presser foot operating at the same speed ratio as the main shaft of the 70 machine.

The thread loop-former driving gear is 75 operated from the top rotary shaft of the machine through suitable gearing by means of a shaft extending down through the hollow presser bar connected to the gear in the presser foot for imparting rotary movement 80 to the thread loop-former. The device is of such construction that it performs accurately at very high speeds, one revolution 85 or cycle for each complete stitch formation.

Other objects of this invention will appear in the following description thereof, reference being had to the accompanying drawings forming a part of this specification, wherein like reference characters indicate corresponding parts in the several views and wherein Fig. 1 is a perspective view 90 of the entire machine, showing the working mechanism in full lines, and the framework of the machine in dotted lines; Fig. 2 is a front end elevational view, partly in section, the needle bar and driving mechanism shown in full lines, and the top portion of 95 the sewing machine head forming the framework, shown in dotted lines; Fig. 3 is a top plan view taken on the line 3—3 of Fig. 2, looking in the direction of the arrow; Fig. 4 is a bottom view of the thread loop cast-off ring; Fig. 5 is a top plan view of the 100 thread loop former carried by the ring shown in dotted lines; Fig. 6 is a detail perspective view of the presser foot carrying 105

the thread loop forming mechanism, illustrating the manner in which the thread loop is cast-off of the thread loop former, with relation to the needles, for the formation of a stitch; Fig. 7 is a detail perspective view, parts being broken away, showing the gearing of the thread loop forming parts, the presser foot being shown in dotted lines; Figs. 8 to 13 inclusive are detail views illustrating the formation of thread loops in the formation of the stitches, and also illustrating the action of the thread controller which at the proper time gives and takes up slack thread during the stitch formation; Fig. 14 is a detail perspective view illustrating the stitches joining two pieces of work; Fig. 15 is an end view of Fig. 14, and illustrates the manner in which the two pieces of work are joined by the needle threads connected on top of the work with the loops of thread, as well as connected on the bottom of the work by the looper threads; Fig. 16 is a perspective view of the circular loop forming plate adapted to be assembled to and carried by the thread loop forming gear, showing the vertical upstanding lug which carries the thread to form the loop; Fig. 17 is a perspective view of the thread loop forming gear, showing the circular upstanding flange over which the loop forming plate fits, and also showing the upstanding lug which aligns with the lug of the circular plate for forming the thread loops; and Fig. 18 is an enlarged sectional view of the presser foot mechanism taken on line 18—18 of Fig. 3, looking in the direction of the arrow.

This invention is an improvement of the cross stitch mechanism, shown in my Patent No. 1,058,820 dated April 15, 1913, wherein two cross threads were used in the formation of the covering stitches on top of the work. The threads were alternately laid in loop form, crossing one another on the center line between the needle stitches, and the device was operated in such manner as to lay the threads first one way at one stitch and then the other way at the next stitch, and so on, alternating as the stitching proceeded, the parts having a rotary oscillatory movement and being operated at a speed of half that of the main shaft. In the construction however, the reversing of the operating mechanism proved to be destructive at high speeds and the parts became shaky and noisy and considerable difficulty was encountered in the threading of the thread carriers, it being necessary to pass the cross threads through several small thread eyelets to get them into position in the gears for proper stitch formation.

This invention is also an improvement on the cross thread laying mechanism of my Patent No. 1,328,108 dated January 13, 1920. In that invention the cross thread carrying finger was given rotary oscillatory move-

ment around the needles by suitable mechanism. The finger, which was carried from above and projected downward, was of considerable length, and set up a whipping action when operated at high speeds, which, although out of the way of the needle threads normally, would interfere therewith each time the needle threads became broken, whereupon the machine had to be turned to a given position by turning the hand wheel in order to re-thread the needles.

All the above disadvantages or objections are done away with in the present improvement, the cross thread carrier in the present instance having a continuous movement around the needles, or a movement in a continuous forward path relatively to the needles, it being understood that by a continuous forward path is meant a path of movement distinguished from a forward and backward path of movement, or an oscillating or reciprocatory path, disclosed for instance in the patents hereinbefore mentioned. Hence in the present case the cross thread carrier moves in a continuous line or direction relatively to the needles. Furthermore, there is no mechanism to obstruct the freedom of threading the needles, or the handling of the work, and in threading the thread loop-former it is merely necessary to lay the end of the thread in the path of the needles, there being no eyelets or thread holes into which the thread must be inserted for guiding it into position for forming the stitches.

Another advantage of the present improvement resides in the manner in which the parts are connected for operation in that the driving mechanism is contained in the head of the machine, and is operated from the top drive shaft, and being entirely enclosed, prevents the throwing of oil and the soiling of goods, the construction being such that very few of the parts have a vertical rise and fall movement though they are connected with the presser foot which has a rise and fall movement because of its cooperation with the usual four-motion feed for feeding the goods. This feature is of considerable importance because it is well known to those skilled in the art that a heavy presser foot mechanism operating at high speed has a tendency to cut and injure the fabrics and causes breakage of throat plates and excessive wear on the feed operating mechanism. With the construction of the present improvement, the number of parts and weight thereof is reduced to a minimum. The presser foot and the thread loop-former carried thereby is capable of being lifted from the work, as occasion requires, either by hand or foot treadle, and when so lifted there is no part of the mechanism to interfere with the needles or needle holders, in case the machine is operated.

The present machine comprises a machine base 1, and a front standard 2 forming a support for the cloth plate 3. The vertical wall 4 of the base forms one portion of a box-shaped section of the machine base, upon which is mounted the overhanging arm, and is attached thereto as at 5. A portion of this arm extends forward as at 6, and affords a seat for holding the rear right hand edge 10 of the cloth plate 3. The overhanging portion of the top arm is indicated at 7, the upright support at 8, and the head of the machine at 9. The bottom shaft 10 operates in any suitable bearings, such as the bushing 15 11 of the rear wall and an intermediate bearing 11^a. The rear end of the bottom shaft 10 carries the belt wheel 12 for operating the machine. Rotary movement of the bottom shaft 10 is transmitted to the top shaft 20 13 by connecting rods 14, cranks 15 on the bottom shaft, and similar cranks 16 on the top shaft. The top shaft 13 operates in bearings 17 and 19 at the rear and front ends respectively of the machine, and carries a hand 25 wheel 18 for turning the machine by hand.

In the present instance the feed mechanism comprises a suitable feed dog 20 for feeding the work, the dog being carried by a feed bar 21 which is pivotally connected at 30 22 by a shaft 23 to the top portion of the feed rocker frame 24, for imparting feeding movement to the feed dog. A pitman 25 also connects the shaft 23 to an adjustable crank 26 by the usual stud and lock nut 27, 35 which is adjustable across the face of the crank disc 28 by means of the screw 29. Rise and fall movements are given to the feed by a lifting eccentric 30, carried by the bottom shaft 10 adjacent to the inner wall 40 of the standard 2. The connection 31 surrounds the eccentric 30, and is pivotally connected to the feed bar 21 by a pin 32. The bottom end of the feed rocker frame 24 is pivoted to the machine base 1 by a stud 33. 45 The looper mechanism comprises a pair of gibbs 34 and 35, secured to the top surface of the base 1, and forming a guideway for the slide 36 extending across the width of the machine base. This slide is provided 50 with upstanding lugs 37 and 39 tapped to receive conical screws 38 and 40 respectively, which are locked by screws 41. Between the conical ends of the screws 38 and 40 is pivotally supported the looper carrier 42, the shank 43 of which is provided with a hub 55 tapped to receive a ball stud 44. The top portion of the looper carrier is provided with a thread-carrying looper 45 and adjacent thereto is secured a needle guard 46. 60 The looper is oscillated in a path transverse to the line of feed by the ball joint 47 carried by the ball stud 44 and connected to the ball joint 48 by a rod 49. The ball joint 48 is pivotally connected to a ball crank 50 formed on a disc 51 carried by a crank shaft

(not shown) which crank shaft operates in suitable bearings of the bracket 52, and is operated by a right-angle spiral gear drive. The driving gear thereof is indicated at 53, which co-acts with a similar gear (not shown) carried by the crank shaft of the disc 51, thereby imparting rotary movement to the crank 50 for oscillating the looper. A detailed description of the construction of the looper drive is deemed unnecessary since 70 it forms no part of this invention, the same being embraced in my Patent No. 1,264,585 dated April 30, 1918.

The needle driving mechanism comprises a crank disc 54, carried at the forward end 80 of the shaft 13, a crank pin 55, and pitman connection 56 pivotally connected to the needle bar 57 through the clamp collar 58, and stud 59, for reciprocating the needle bar vertically in the bearings 60. The lower end 85 of the needle bar carries the usual needle holder 61, for the reception of the needles 62. Any suitable conducting means for threads 64 are provided, such as guides 63, thread guide 66 secured to a post 65, guide 90 67 secured to the arm 7 as at 68, tensions 69, and entrant guides 70.

The looper thread 71 is conducted to the looper by a slotted tube 72, (see Fig. 1) which is supported by brackets 73, carried 95 by the front edge of the machine base 1. The take-up mechanism generally indicated by 74 need not be described as it forms no part of this invention, but is described in my Patent No. 1,328,023 dated January 13, 100 1920.

The presser foot mechanism comprises a presser foot bottom 75 having an upturned toe 76, and a lateral projecting portion 77 for guiding tubing, lace and the like into proper 105 position for the needles. The presser foot bottom is dovetailed into the presser foot 78, which is provided with a shank 79, tapped at 80 to receive clamp screws for securing the presser foot to the presser tube 81 by 110 means of clamp 82. The presser tube 81 operates vertically in a bushing 83, which is secured in the head 9 of the machine. Clamped to the upper end of the presser tube 81 by means of a screw 85 is a guide 84, 115 the rear end of which projects through a guide slot in the head 9 to prevent the tube 81 from turning the free end of the guide. This guide carries a vertical wire 86 secured therein by a screw 87. The top end 120 of the wire (not shown) is curved to encircle the end 88 of the usual presser lifter lever 89 pivotally secured to the rear wall of the arm 7. Pivoted to the rear end of the lever 89 as at 90 is the presser lifting rod 91, which extends down through the machine and connects with the usual foot treadle or knee lift (not shown) for lifting the presser foot, the hands of the operator thus being free to manipulate the work. In 130

addition to the foot or knee lifter means, the usual hand lifter 92 pivotally secured at 93 in the guiding slot of the machine head 9 is provided, the same adapted to coact 5 with the guide 84 for lifting the presser foot. Above the guide 84 is mounted a collar 94 provided with a slot on the rear side for the reception of the end 95 of the presser spring 96. An adjusting screw and lock nut 10 98 regulates the pressure of the spring for holding the presser foot down on the work.

The top stitch forming mechanism consists of a driving gear 99, carried by the top shaft 13, and driven by the crank disc 54, 15 pins 100 connecting the gear with the disc for rotary movement therewith. The gear 99 is in mesh with a gear 101 of equal diameter, which is provided with a collar through 20 which the screws 102 pass for securing it to a shaft 103 operating in bearings 104 and 105. A spiral gear 106 is secured to the shaft 103 and is in mesh with a spiral gear 107 slidably keyed to a vertical shaft 108 by a key 109, operating in a groove 110. 25 The gears 106 and 101 are entirely enclosed in a casting 111 secured by screws 113 to a bracket 112, the latter being secured to the bearing 19 by screws 114, and bored to fit over the reduced end 115 of the bearing 30 19. By this construction proper alinement of the gears with respect to the top shaft 13 and the vertical shaft 108 is obtained at all times, and important advantages in the manufacture, assembling and oiling of the 35 parts is furthermore obtained as a result thereof.

The shaft 108 is constructed to form bearings 116 and 117 in each end of the tube 81, and intermediate these bearings the shaft is 40 reduced in diameter as indicated at 118. The top 119 of the shaft 108 is conical and operates in a conical seat in the yoke 120, which is provided with a collar 122 secured as at 123 to the upper end of the tube 81.

45 By reason of the conical end 119 seated in the yoke, and an enlarged shoulder formed by the upper portion of the shaft 108 resting on the top of the tube 81 the shaft 108 is restricted from vertical movement relative to the tube 81. It will thus be seen by this construction that the rise and fall movement of the tube 81 gives similar rise and fall movement to the shaft 108, and the same is maintained at all times in proper cooperative 50 relation with the tube 81. The upper section of the shaft 108 operates in bearings 124, one above and one below the gear 107, the bearings thus forming a housing for confining the gear 107 therebetween and permitting the shaft 108 to rotate and operate 55 vertically therein and within the gear 107.

The lower end 117 of the shaft 108 is provided with a semicircular key 125, which fits into a semi-circular opening 126 of a 60 gear 127 carried in a recess in the bottom

of the presser foot, the recess being of such diameter and depth as to permit free rotary movement of the gear. This gear 127 meshes with an intermediate gear 128, also carried in a recess in the bottom of the presser foot, the recess being of suitable depth and diameter to permit the gear to rotate freely on a stud 129 rigidly secured to the presser foot.

The intermediate gear 128 meshes with 75 the thread loop forming gear 130, operating in a recess in the presser foot of suitable depth and diameter to permit free rotary movement of the gear. Carried by the loop forming gear 130 is a circular plate 131 80 (see Fig. 5) secured thereto in any suitable manner, so that the plate and gear are substantially an integral operating unit. The plate is provided with a vertical up-standing thread loop forming lug 133, so shaped at one end 134 to permit it to pick up a strand of thread and carry such thread around in loop form as hereinafter described. The gear 130 is provided with a circular flange 132 extending vertically and equal to the thickness of the circular plate 131. The outside diameter of the flange is equal to the diameter of the hole 131^A, the same being a pressed fit over the circular flange 132, and being provided with one or more notches 131^B into which a portion of the flange 132 may be swaged laterally so as to interlock the parts and prevent relative movement. The flange 132 is formed with a lug 132^A which substantially 90 corresponds in form to lug 133. When assembled the parts are located so as to aline 95 with one another, as shown in Figs. 8 to 13 inclusive, a channel 135 being formed therebetween by the ledge 135^A (see Fig. 16). By making the lugs integral with the parts 130 and 131, the manufacture thereof is greatly facilitated, and inasmuch as the lugs 133 and 132^A are usually not over $\frac{3}{16}$ inch in thickness, and inasmuch as it is 100 important to have the parts durable for high speed operation, the integral construction of the lugs prevents any danger of their becoming knocked off or broken while in use, and a further advantage of this construction resides in the fact that in case either of the parts wears or becomes damaged, a duplicate can be readily substituted 105 without necessitating the renewal of both parts.

The channel 135 is provided for the purpose of permitting the entrance between the lugs of a thread loop cast-off finger 136 carried by circular plate 136^A. The cast-off 110 is formed from a circular rib 137, the bottom edge thereof resting upon the upper face of the thread loop former plate 131 and operating in the channel 135. The end of the cast-off is inclined downwardly as at 138 to form a point 139 adapted to pass in 115 120 125 130

under, pick up and cast off the loop 140 of the top thread 141 (see Fig. 6) each time the thread loop former rotates to a position where the loop will be entered by one of the needles. The location of the cast-off finger point 139, with respect to the left hand needle 62, is such as to insure the needle entering the loop of cross-thread, as shown in Figs. 3 and 6, before the thread is drawn away from the lugs 133 and 132^A of the thread loop forming members. Adjacent to the circular rib 137 and spaced therefrom is an annular rib 142 fitting into a recess in the top of the presser foot for centralizing and locating the same. The bottom edge of this annular rib engages the outer edge of the thread loop former plate 131 for holding it in place for free rotary movement in the presser foot.

20 A flange 145 of plate 136^A overlaps the top surface of the presser foot (see Figs. 6, 7 and 18) and is secured to the presser foot as by screws 146. The annular rib and the flange are cut away as indicated at 147 (see Figs. 3, 4, 6 and 7) to align with a channel 148 cut into the presser foot for the entrance of the cross-thread 141. Crossing the mouth of this channel is an open thread hook 149 for guiding the cross-thread to the stitching position.

In advance of the rib 137 is a space 137^A approximately equal in length to the lugs 133 and 132^A for permitting the loops of thread when cast from the lugs to escape through such space, and to draw up close to the needle. Diametrically opposite the rib 137 is a similar rib 137^B the latter being spaced from plate 131 to provide a space or slot 137^D as shown in Fig. 18 to permit the thread which forms the loops of the top stitch to pass thereunder as it is being carried around in front of the needle in the loop formation. It will be noted that this rib 137^B operates as a guide or hold-down device adapted to prevent the thread from jumping over the top of the lugs 133 and 132^A while it is carrying the thread from the position shown in Fig. 10 to the position shown in Fig. 12. With reference to Fig. 18, it will be noted that there is a small space 137^E between the annular rib 142 and the lug 133 sufficient in size for passage of the thread 141 as it is carried around in loop form. Such space is necessary since otherwise the thread would be wedged between the parts and broken.

The top cross thread 141 is conducted to the thread hook 149 through the U-shaped thread eyelet 150, secured by a screw 151 and lug 152 to the face plate 153 indicated by dotted lines in Fig. 3. The U-shaped thread eyelet receives the thread 141 as it passes from the tension 154. The latter comprises a tension post 155, tension spring 156, and adjusting nuts 157 for regulating

the tension on the thread. A guide eye 158 conducts the thread to the tension 154 as the thread is led from the usual thread stand (not shown). The tension 154 is carried by an angle bracket 159 secured to the lug 152 by screws 160. Co-acting with the U-shaped eyelet 150 is a rotary eccentric disk 161, secured to the end of the shaft 103 as by a screw 162, and rotating with the shaft in the direction of the arrow in Fig. 1 to engage the thread 141 at the proper time during the operation of the thread loop former to draw slack thread through the tension 154, and also in co-operation with the tension 154 to hold the thread taut and under tension at another time during the action of the thread loop former upon the thread.

With reference to Figs. 8 to 13 inclusive, the thread loop former 131 rotates in the direction of the arrow and picks up a strand of thread 141 and carries it around the needles 62 in loop form as shown in Fig. 8. In this position of the loop of thread the same is ready to be cast off of the lugs 133 and 132^A by the cast-off 138 operating between the lugs 133 and 132^A, the location of the cast-off being slightly in the rear and to the left of the left hand needle. Thus it will be seen that the strand A is carried to the rear of both needles, and that the length of the lugs 133 and 132^A is such as to carry the strand B of the thread 141 in front of the left hand needle, thereby insuring the needle passing into the loop formed by the strands A and B of the thread. The portion of the strand B indicated at C is in the rear of the right hand needle, inasmuch as the thread hook 149 is positioned to the right and rear of the right hand needle, and lies at an angle to bring it in between the two needles as shown.

As illustrated in Fig. 9, the thread loop former rotates to a position where the thread loop is cast off of the lugs 133 and 132^A, the cast-off 138 passing directly between the lugs 133 and 132^A, and the loop of thread being drawn close to the left hand needle by the take-up action of the disk 161. The strand A is being stitched down by the needle loop D, while the strand B and the portion C is being stitched down by the needle thread loop E. In Fig. 10, the thread loop former has rotated to a position where it has picked up and begun to carry the thread 141 to form a loop and bring it into position for the needles. In Fig. 11 the thread loop formed as shown in Fig. 10, has been carried to a position directly in front of the needles, and in this position the strand B of thread is brought close to the right hand needle. In Fig. 12, the thread loop former has rotated still further around the needles, carrying the strand A of the loop directly in front

of and across the needles, and in Fig. 13 the loop of thread is shown in position for the entrance of the left hand needle into the loop, the strand A being in back of the left hand needle, and the strand B being in back of the right hand needle. The loop is in position to be cast off by the cast-off 138 upon the further movement of the thread loop former for the completion of the stitch. 10 The feeding of the work takes place during each complete rotary movement of the thread loop former for the purpose of spacing the lengths of stitches as usual. The feed has completed its movement when the thread loop former has reached the position shown in Fig. 8. The feed is moving downward when the thread loop former has reached the position of Fig. 9, and is moving forward when the thread loop former reaches the position shown in Fig. 10. The work is being fed when the thread loop former is moving to the position of Figs. 11, 12 and 13, completing the cycle. 15 The feed movement is a very important factor in the laying of the stitches, due to the fact that short stitches are very difficult to make with a mechanism that merely reciprocates to and fro in front of the needles inasmuch as the advancement of the work, 20 as each stitch is formed, is relied upon to carry the strands of thread, forming the cross-stitches to be stitched down by the needle loops past the needles. This disadvantage resulting from such feeding of the cross thread loops past the needles is overcome in the present improvement wherein the cross-thread loop former has a continuous circular or rotary movement in a continuous path or direction. Thus the loop 25 former being a rotary device, moving round and round the needles, the thread is carried by the loop former directly behind the needles, however short the stitches may be. To aid in the formation of the stitches, 30 the rotary thread controller 161 is timed to act upon the thread 141 so as to both take up slack and give slack. In Fig. 8 the controller is illustrated as taking up the slack in the thread between the eyelet 149 and the 35 stitch mechanism. The take-up rotates to draw or take up the loop as it is cast off the lugs 133 and 132^A, as shown in Fig. 9 thereby partly closing the loop around the left hand needle. The loop is further drawn up 40 around the needle, as shown in Fig. 10 by the movement of the lugs 133 and 132^A, taking up the thread and carrying it in loop form around the right hand needle. In 45 this position the take-up 161 is shown giving up thread to form the loop shown in Figs. 11 and 12, while in Fig. 13, the take-up 161 is beginning to act on the thread to tighten it or place it under tension as the loop moves to the position to be cast off 50 of the lugs 133 and 132^A. The amount of

friction applied to the thread by the tension 55 154 controls the size of the top thread loops, a tight tension having a tendency to narrow the stitch and a loose tension having a tendency to broaden it. 70

In Figs. 14 and 15 two pieces of goods are shown stitched together, the body fabric being indicated at 163, and the tubular fabric at 164. The inner portions of the two fabrics overlap one another at 165, and 75 are secured by the needle thread loops 166 on top of the work, interlaced by the cross thread loops 167, the needle threads being concatenated on the bottom of the work by the looper thread stitches 168. 80

As shown in Fig. 2, the feed dog 20 cooperates with a throat plate P for feeding the work, the throat plate having the usual needle holes and tongue Q, over which the looper thread stitches are formed. The 85 presser foot bottom 75 may also be provided with a tongue R (Fig. 6) projecting in between the needles, over which the cross stitches may be formed on top of the work. The length and shape of the throat plate 90 and presser foot tongues Q and R may be varied to suit the character of work. On delicate fabrics such tongues are desirable in order to clamp the goods between them at the time the needles enter the work and at 95 the time of drawing up the stitches, while on more rigid fabrics such tongues are not always required. 100

Although I have described my invention in its preferred form, it is to be understood that I do not limit myself to the construction herein shown and described, except in so far as defined in the appended claims and embraced within the scope thereof. 105

I claim as my invention:

1. In a sewing machine, the combination of stitching mechanism, looper mechanism, cross thread carrying means movable in a continuous direction, and thread conducting means operative to conduct the thread to the cross thread carrying means, said thread conducting means being restrained from rotation about said stitching mechanism. 110

2. In a sewing machine, the combination of stitching mechanism, looper mechanism cooperating therewith, rotary cross thread carrying means movable in a continuous direction around the stitching mechanism, and thread conducting means operative to conduct the thread to the cross thread carrying means, said thread conducting means being restrained from rotation about said mechanism. 115

3. In a sewing machine, the combination of stitching mechanism comprising a needle bar carrying a plurality of needles, cross thread carrying means having the axis thereof substantially coincident with the axis of the needle bar cooperating therewith and movable in a continuous direction, and 120

130

thread conducting means operative to conduct the thread to the cross thread carrying means, said thread conducting means being restrained from rotation about said stitching mechanism.

4. In a sewing machine, the combination of stitching mechanism comprising a needle bar carrying a plurality of needles, looper mechanism, and cross thread carrying means 10 cooperating therewith and movable in a continuous direction, said cross thread carrying means including means for intermittently engaging the thread.

5. In a sewing machine, the combination of stitching mechanism comprising a needle bar carrying a plurality of needles, rotary cross thread carrying means cooperating therewith and movable in a non-reciprocal 15 path around the path of the needles, and fixed means for guiding the thread thereto.

6. In a sewing machine, the combination of stitching mechanism comprising a needle bar carrying a plurality of needles, rotary cross thread carrying means cooperating therewith and movable in a continuous circular direction around the needles, and thread conducting means operative to conduct the thread to the cross thread carrying 20 means, said thread conducting means being restrained from rotation about said mechanism.

7. In a sewing machine, the combination of stitching mechanism, looper mechanism, and cross thread carrying means movable in a continuous direction and including means adapted to engage and be disengaged from the thread during such movement.

8. In a sewing machine, the combination of stitching mechanism comprising a needle bar carrying a plurality of needles, rotary cross thread carrying means movable horizontally in a continuous non-reciprocal path relatively to the needles, and including means adapted to engage and be disengaged from the thread during such movement.

9. In a sewing machine, the combination of stitching mechanism comprising a needle bar carrying a plurality of needles, and a rotary cross thread carrying means comprising a plurality of spaced projecting members movable horizontally in a continuous path relatively to the needles, and adapted to engage and be disengaged from the thread.

10. In a sewing machine, the combination of stitching mechanism comprising a needle bar carrying a plurality of needles, rotary cross thread carrying means comprising an upright member movable horizontally in a continuous circular non-oscillatory path relatively to the needles, for intermittently engaging the thread.

11. In a sewing machine, the combination

of stitching mechanism comprising a needle bar carrying a plurality of needles, rotary cross thread carrying means comprising an upright member movable in a continuous circular non-reciprocal path around the path of the needles, and thread conducting means operative to conduct the thread to the cross thread carrying means, said thread conducting means being restrained from rotation about said mechanism. 70

12. In a sewing machine, the combination of stitching mechanism comprising a needle bar carrying a plurality of needles, and rotary cross thread carrying means comprising a plurality of spaced upright thread-engaging members movable in a continuous path about the needles for intermittently engaging the thread. 75

13. In a sewing machine, the combination of stitching mechanism comprising a plurality of needles, a cross-thread carrying means cooperating therewith and movable in a continuous path around the needles, and cast-off means cooperating with said cross-thread carrying means at predetermined times. 80

14. In a sewing machine, the combination of stitching mechanism comprising a plurality of needles, looper mechanism cooperating with the needles, a rotary cross-thread carrying means cooperating therewith and movable in a continuous path around the needles, and cast-off means cooperating with said cross-thread carrying means at predetermined times. 85

15. In a sewing machine, the combination of stitching mechanism comprising a needle bar carrying a plurality of needles, a cross-thread carrying means having its axis substantially coincident with the axis of the needle bar cooperating therewith and movable in a continuous path relatively to the needles, and cast-off means cooperating with said cross-thread carrying means at predetermined times. 90

16. In a sewing machine, the combination of stitching mechanism comprising a needle bar carrying a plurality of needles, looper mechanism cooperating therewith, a rotary cross-thread carrying means cooperating therewith and movable in a continuous path relatively to the needles, and cast-off means cooperating with said cross-thread carrying means at predetermined times. 100

17. In a sewing machine, the combination of stitching mechanism comprising a needle bar carrying a plurality of needles, a rotary cross-thread carrying means cooperating therewith and movable in a circular path around the path of the needles, and cast-off means cooperating with said cross-thread carrying means at predetermined times. 105

18. In a sewing machine, the combination of stitching mechanism comprising a needle

- bar carrying a plurality of needles, a rotary cross-thread carrying means cooperating therewith and movable in a continuous circular path around the needles, and cast-off means cooperating with said cross-thread carrying means at predetermined times. 19. In a sewing machine, the combination of stitching mechanism comprising a needle bar carrying a pair of needles, a cross-thread carrying means comprising a projecting member adapted to rotate in a continuous path around the needles, and cast-off means cooperating with said cross-thread carrying means at predetermined times. 20. In a sewing machine, the combination of stitching mechanism comprising a needle bar carrying a plurality of needles, a rotary cross-thread carrying means comprising an upright member movable in a continuous substantially horizontal path relatively to the needles, and cast-off means cooperating with said cross-thread carrying means at predetermined times. 21. In a sewing machine, the combination of stitching mechanism comprising a needle bar carrying a plurality of needles, looper mechanism cooperating therewith, a rotary cross-thread carrying means comprising a plurality of spaced projecting members movable in a continuous path relatively to the needles, and cast-off means cooperating with said cross-thread carrying means at predetermined times. 22. In a sewing machine, the combination of stitching mechanism comprising a needle bar carrying a plurality of needles, looper mechanism cooperating therewith, a rotary cross-thread carrying means comprising an upright member movable in a continuous circular path relatively to the needles, and cast-off means cooperating with said cross-thread carrying means at predetermined times. 23. In a sewing machine, the combination of stitching mechanism comprising a needle bar carrying a plurality of needles, a rotary cross-thread carrying means comprising an upright member movable in a continuous circular path around the path of the needles, and cast-off means cooperating with said cross-thread carrying means at predetermined times. 24. In a sewing machine, the combination of stitching mechanism comprising a needle bar carrying a plurality of needles, a rotary cross-thread carrying means comprising a plurality of spaced upright members movable in a continuous path around the needles, and cast-off means cooperating with said cross-thread carrying means at predetermined times. 25. In a sewing machine, the combination of stitching mechanism comprising a needle bar carrying a plurality of needles, looper mechanism cooperating with said needles, presser foot mechanism, and cross-thread carrying means supported by said presser foot mechanism and rotatable in a continuous direction around the needles. 26. In a sewing machine, the combination of stitching mechanism comprising a needle bar carrying a plurality of needles, a rotary cross-thread carrying means cooperating therewith and movable in a continuous path around the needles, cast-off means cooperating with said cross-thread carrying means at predetermined times, and rotary take-up means effective synchronously with said cast-off means. 27. In a sewing machine, the combination of stitching mechanism comprising a needle bar carrying a plurality of needles, a rotary cross-thread carrying means cooperating therewith and movable in a circular path around the path of the needles, cast-off means cooperating with said cross-thread carrying means at predetermined times, and rotary take-up means effective synchronously with said cast-off means. 28. In a sewing machine, the combination of stitching mechanism comprising a needle bar carrying a pair of needles, a cross-thread carrying means comprising a projecting member adapted to rotate in a continuous path around the needles, cast-off means cooperating with said cross-thread carrying means at predetermined times, and rotary take-up means effective synchronously with said cast-off means. 29. In a sewing machine, the combination of stitching mechanism comprising a needle bar carrying a plurality of needles, a rotary cross-thread carrying means comprising a plurality of spaced projecting members movable in a continuous path relatively to the needles, cast-off means cooperating with said cross-thread carrying means at predetermined times, and rotary take-up means effective synchronously with said cast-off means. 30. In a sewing machine, the combination of stitching mechanism comprising a needle bar carrying a plurality of needles, looper mechanism cooperating with said needles, presser foot mechanism, and cross-thread carrying means supported by said presser foot mechanism and rotatable in a continuous direction around the needles. 31. In a sewing machine, the combination of stitching mechanism comprising a needle bar carrying a plurality of needles, looper mechanism cooperating with said needles, presser foot mechanism, and rotary cross-thread carrying means supported by said presser foot mechanism and rotatable in a continuous direction around the needles. 32. In a sewing machine, the combination

of stitching mechanism comprising a needle bar carrying a plurality of needles, looper mechanism cooperating with said needles, presser foot mechanism, and rotary cross-thread carrying means carried by said presser foot mechanism and having its axis substantially alined with the axis of the needle bar and movable in a non-reciprocatory path around the path of the needles.

33. In a sewing machine, the combination of stitching mechanism comprising a needle bar carrying a plurality of needles, looper mechanism cooperating with said needles, presser foot mechanism, and cross-thread carrying means carried by said presser foot mechanism and movable in a continuous path relatively to the needles, and cast-off means carried by said presser foot mechanism and adapted to cooperate with said cross-thread carrying means at predetermined times.

34. In a sewing machine, the combination of stitching mechanism comprising a needle bar carrying a plurality of needles, looper mechanism cooperating with said needles, presser foot mechanism, rotary cross-thread carrying means supported by said presser foot mechanism and rotatable in a continuous path around the needles, and cast-off means carried by said presser foot mechanism and adapted to cooperate with said cross-thread carrying means at predetermined times.

35. In a sewing machine, the combination of stitching mechanism comprising a needle bar carrying a plurality of needles, looper mechanism cooperating with said needles, presser foot mechanism, rotary cross-thread carrying means supported by said presser foot mechanism having its axis substantially alined with the axis of the needle bar and movable in a circular path around the path of the needles, and cast-off means cooperating therewith.

36. In a sewing machine, the combination of stitching mechanism comprising a needle bar carrying a plurality of needles, looper mechanism cooperating with said needles, presser foot mechanism, cross-thread carrying means carried by said presser foot mechanism and movable in a continuous path relatively to the needles, cast-off means carried by said presser foot mechanism and adapted to cooperate with said cross-thread carrying means at predetermined times, and rotary take-up means operative upon the thread simultaneously with said cast-off means.

37. In a sewing machine, the combination of stitching mechanism comprising a needle bar carrying a plurality of needles, looper mechanism cooperating with said needles, presser foot mechanism, rotary cross-thread carrying means supported by said presser foot mechanism and rotatable in a continu-

ous path around the needles, cast-off means carried by said presser foot mechanism and adapted to cooperate with said cross-thread carrying means at predetermined times, and rotary take-up means operative upon the thread simultaneously with said cast-off means.

38. In a sewing machine, the combination of stitching mechanism comprising a needle bar carrying a plurality of needles, looper mechanism cooperating with said needles, presser foot mechanism, rotary cross-thread carrying means supported by said presser foot mechanism and having its axis substantially alined with the axis of the needle bar and movable in a circular path around the path of the needles, cast-off means operative upon the thread at predetermined times and rotary take-up means operative upon the thread simultaneously with said cast-off means.

39. In a sewing machine, the combination of stitching mechanism comprising a needle bar carrying a plurality of needles, looper mechanism cooperating with said needles, presser foot mechanism, a thread guide supported to one side and out of alinement with the needles, cross-thread carrying means carried by the presser foot mechanism and comprising one or more projecting members movable in a continuous rotary non-oscillatory path relatively to the path of the needles and adapted to engage the thread from said thread guide and carry the same to a loop-forming position.

40. In a sewing machine, the combination of stitching mechanism comprising a needle bar carrying a plurality of needles, looper mechanism cooperating with said needles, presser foot mechanism, a thread guide supported to one side and slightly in the rear of one of the needles, and cross-thread carrying means supported by the presser foot mechanism and comprising one or more projecting members movable in a continuous non-oscillatory path about the needles and adapted to engage the thread from said thread guide and carry the same to a loop-forming position.

41. In a sewing machine, the combination of stitching mechanism comprising a needle bar carrying a plurality of needles, looper mechanism cooperating with said needles, presser foot mechanism, a thread guide supported by the presser foot mechanism to one side and slightly in the rear of one of the needles, and cross-thread carrying means supported by the presser foot mechanism and having the axis thereof substantially alined with the axis of the needle bar and comprising one or more projecting members movable in a continuous non-oscillatory path about the needles and adapted to engage the thread from said thread guide and carry the same to a loop-forming position.

42. In a sewing machine, the combination of stitching mechanism comprising a needle bar carrying a plurality of needles, looper mechanism cooperating with said needles, presser foot mechanism, a thread guide supported to one side and slightly in the rear of one of the needles, cross-thread carrying means supported by the presser foot mechanism and comprising one or more projecting members movable in a continuous path about the needles and adapted to engage the thread from said thread guide and carry the same to a loop-forming position, and means effective at predetermined times to cast off the thread from said cross-thread carrying means.

10 43. In a sewing machine, the combination of stitching mechanism comprising a needle bar carrying a plurality of needles, looper mechanism cooperating with said needles, presser foot mechanism, a thread guide supported by the presser foot mechanism to one side and slightly in the rear of one of the needles, cross-thread carrying means supported by the presser foot mechanism and having the axis thereof substantially aligned with the axis of the needle bar and comprising one or more projecting members movable in a continuous path about the needles and adapted to engage the thread from said thread guide and carry the same to a loop-forming position, and means effective at predetermined times to cast off the thread from said cross-thread carrying means.

20 44. In a sewing machine, the combination of stitching mechanism comprising a needle bar carrying a plurality of needles, looper mechanism cooperating with said needles, presser foot mechanism, a thread guide supported to one side and slightly in the rear of one of the needles, cross-thread carrying means supported by the presser foot mechanism and comprising one or more projecting members movable in a continuous path about the needles and adapted to engage the thread from said thread guide and carry the same to a loop-forming position, means effective at predetermined times to cast off the thread from said cross-thread carrying means, and rotary means effective at predetermined times for drawing a loop around one of the needles.

30 45. In a sewing machine, the combination of stitching mechanism comprising a needle bar carrying a plurality of needles, looper mechanism cooperating with said needles, presser foot mechanism, a thread guide supported by the presser foot mechanism to one side and slightly in the rear of one of the needles, cross-thread carrying means supported by the presser foot mechanism and having the axis thereof substantially aligned with the axis of the needle bar and comprising one or more projecting members movable in a continuous path about the needles

and adapted to engage the thread from said thread guide and carry the same to a loop-forming position, means effective at predetermined times to cast off the thread from said cross-thread carrying means, and rotary means effective at predetermined times for drawing a loop around one of the needles.

46. In a sewing machine, the combination of stitching mechanism comprising a needle bar carrying a plurality of needles, looper mechanism cooperating with said needles, presser foot mechanism, a thread guide supported to one side and slightly in the rear of one of the needles, cross-thread carrying means supported by the presser foot mechanism and comprising one or more projecting members movable in a continuous path about the needles and adapted to engage the thread from said thread guide and carry the same to a loop-forming position, means effective at predetermined times to cast off the thread from said cross-thread carrying means, and rotary means effective at predetermined times and simultaneously with said cast-off means for drawing a loop around one of the needles, said cross-thread carrying means being effective at predetermined times to draw a loop around a second needle.

55 47. In a sewing machine, the combination of stitching mechanism comprising a needle bar carrying a plurality of needles, looper mechanism cooperating with said needles, presser foot mechanism, a thread guide supported by the presser foot mechanism to one side and slightly in the rear of one of the needles, cross-thread carrying means supported by the presser foot mechanism and having the axis thereof substantially aligned with the axis of the needle bar and comprising one or more projecting members movable in a continuous path about the needles and adapted to engage the thread from said thread guide and carry the same to a loop-forming position, means effective at predetermined times to cast off the thread from said cross-thread carrying means, and rotary means effective at predetermined times and simultaneously with said cast-off means for drawing a loop around one of the needles, said cross-thread carrying means being effective at predetermined times to draw a loop around a second needle.

60 48. In a sewing machine, the combination of stitching mechanism comprising a needle bar carrying a plurality of needles, looper mechanism cooperating with said needles, presser foot mechanism, a thread guide supported to one side and slightly in the rear of one of the needles, cross-thread carrying means supported by the presser foot mechanism and comprising one or more projecting members movable in a continuous path about the needles and adapted to engage the thread from said thread guide

- and carry the same to a loop-forming position, means effective at predetermined times to cast off the thread from said cross-thread carrying means and comprising an inclined finger, and rotary means effective at predetermined times to draw a loop around one of the needles, said cross-thread carrying means being subsequently operative to form a loop around a second needle. 65
- 10 49. In a sewing machine, the combination of stitching mechanism comprising a needle bar carrying a plurality of needles, looper mechanism cooperating with said needles, presser foot mechanism, a thread guide supported by the presser foot mechanism to one side and slightly in the rear of one of the needles, cross-thread carrying means supported by the presser foot mechanism and having the axis thereof substantially aligned 70 with the axis of the needle bar and comprising one or more projecting members movable in a continuous path about the needles and adapted to engage the thread from said thread guide and carry the same 75 to a loop-forming position, means effective at predetermined times to cast off the thread from said cross-thread carrying means and comprising an inclined finger, and rotary means effective at predetermined times to draw a loop around one of the needles, said cross-thread carrying means being subsequently operative to form a loop around a second needle. 80
- 15 50. In a sewing machine, the combination of stitching mechanism comprising a pair of substantially vertical operating needles, presser foot mechanism, a thread guide supported adjacent thereto for guiding a cross-thread to said stitching mechanism, cross-thread carrying means rotatable in a continuous path about said needles and having a projecting member adapted to engage said cross-thread at predetermined times and carry the same to a loop-forming position, 85 means effective at predetermined times for casting off the loop from said projecting member, and means for drawing said loop around one of the needles, said cross-thread carrying means being operative to draw a loop around a second needle. 90
- 20 51. In a sewing machine, the combination of stitching mechanism comprising a plurality of needles, cross-thread carrying means cooperating therewith and movable in a continuous rotary path around the needles, means effective at predetermined times to cast off the thread from said cross-thread carrying means, and means operative simultaneously with said cast-off means for drawing a loop around a needle. 95
- 25 52. In a sewing machine, the combination of stitching mechanism, cross stitching mechanism cooperating therewith and comprising means having spaced thread engag- 100
- 30 ing members, and means for moving said members in a path to engage and be disengaged from the thread. 105
- 35 53. In a sewing machine, the combination of stitching mechanism, cross-stitching mechanism cooperating therewith and comprising a ring-shaped member having a thread-engaging projection adapted to engage and be disengaged from the thread, and means controlled by said stitching mechanism for rotating said ring-shaped member about said needles in a continuous direction. 110
- 40 54. In a sewing machine, the combination of stitching mechanism, and cross-stitching mechanism cooperating therewith and comprising a ring-shaped member having a thread-engaging projection and adapted to move in a continuous direction about said needles and to engage and be disengaged from the thread. 115
- 45 55. In a sewing machine, the combination of stitching mechanism, cross-stitching mechanism cooperating therewith and comprising means having a thread-engaging projection, and cast-off means comprising a projecting member adapted to cooperate with said projection at predetermined times. 120
- 50 56. In a sewing machine, the combination of stitching mechanism, presser foot mechanism, and cross-stitching mechanism carried by said presser foot mechanism and comprising rotatable means having thread-engaging members and means cooperating therewith at predetermined times for engaging the thread. 125
- 55 57. In a sewing machine, the combination of stitching mechanism comprising a pair of needles, presser foot mechanism having a recess therein, cross-stitching mechanism carried in said recess and comprising a ring-shaped member provided with gear teeth and a pair of projecting thread-engaging lugs, one spaced from the other, a gear cooperating with said teeth for rotating said member in a continuous path about the needles, and a cast-off device comprising a ring-shaped member having a depending finger adapted to project between said lugs at predetermined times. 130
- 60 58. In a sewing machine, the combination of stitching mechanism comprising a pair of needles, and cross-stitch forming mechanism cooperating therewith and comprising a pair of ring-shaped members provided with a pair of spaced thread-engaging projections adapted to rotate in a continuous path about the needles. 135
- 65 59. In a sewing machine, the combination of stitching mechanism comprising a pair of needles, and cross-stitch forming mechanism cooperating therewith and comprising a pair of interconnected members provided with a pair of spaced thread-engaging pro-

- jections adapted to rotate in a continuous path about the needles, one of said members comprising a ring gear and the other a ring plate.
- 5 60. In a sewing machine, the combination of stitching mechanism comprising a pair of needles, cross-stitch forming mechanism cooperating therewith and comprising means provided with spaced thread-engaging projections adapted to rotate in a continuous path about the needles, and cast-off means comprising a finger adapted to project at predetermined times between said spaced projections.
- 10 61. In a sewing machine, the combination of stitching mechanism, cross stitch forming mechanism cooperating therewith and comprising means provided with a pair of spaced thread-engaging projections adapted to rotate in a continuous direction, and means adapted to project between said projections at predetermined times.
- 15 62. In a sewing machine, the combination of stitching mechanism comprising a needle bar and a pair of needles carried thereby, an operating shaft therefor, presser foot mechanism, a cross-thread guide, cross-stitch forming mechanism carried by said presser foot mechanism and comprising a rotary member having a thread-engaging part adapted to rotate in a continuous direction about said needles, means connected to said first shaft for operating said rotary member and comprising a shaft operable in a plane transverse to said first shaft, and a gear carried by said presser foot.
- 20 63. In a sewing machine, the combination of stitching mechanism comprising a needle bar and a pair of needles carried thereby, an operating shaft therefor, presser foot mechanism, a cross-thread guide, cross-stitch forming mechanism carried by said presser foot mechanism and comprising a rotary member having a thread-engaging part adapted to rotate in a continuous path about said needles, means connected to said first shaft for operating said rotary member and comprising a shaft operable in a plane transverse to said first shaft, a gear carried by said presser foot, said cross-stitch forming mechanism being operative to carry a thread loop from said guide, means operative at predetermined times to cast off the loop from said cross-stitch forming mechanism, and rotary means connected to said first shaft for drawing the loop at predetermined times around a needle, said cross-stitch forming mechanism being subsequently operative to draw a loop around the other needle.
- 25 64. In a sewing machine, the combination of stitching mechanism, presser foot mechanism, cross-stitching mechanism carried by said presser foot mechanism and comprising thread engaging means rotatable in a continuous direction, and a common means for operating said stitching and cross-stitching mechanism at a uniform speed ratio.
- 30 65. In a sewing machine, the combination of stitching mechanism, presser foot mechanism, cross-stitching mechanism mounted in said presser foot mechanism, rotary thread control means, driving means for the stitching mechanism, driving means for the cross-stitching mechanism, driving means for the rotary thread control means, and means for operatively interconnecting all of said driving means.
- 35 66. In a sewing machine, the combination of needle mechanism, a presser foot, a presser foot supporting bar therefor, cross-stitching mechanism carried by said presser foot, a driving shaft for the needle mechanism, a driving shaft carried by the presser foot bar for the cross-stitching mechanism, and means for interconnecting said driving shafts whereby the same will rotate at a uniform speed ratio, and said second driving shaft will rotate continuously in one direction.
- 40 67. A sewing machine having stitching mechanism and looper mechanism cooperating therewith, a cross thread carrier movable continuously in one direction, thread conducting means operative to conduct the thread to the cross thread carrier, said thread conducting means being restrained from rotation about said stitching mechanism and operating means for said carrier.
- 45 68. A sewing machine having stitching mechanism and a cross thread carrier movable in a continuous substantially horizontal direction to engage and disengage the thread, and operating means for said carrier comprising a rotary shaft connected therewith.
- 50 69. A sewing machine having stitching mechanism and looper mechanism cooperating therewith, a cross thread carrier movable in a continuous direction to intermittently engage the thread, means for conducting the thread thereto, operating means for said carrier comprising a rotary shaft connected therewith, and a driving shaft connected with said rotary shaft.
- 55 70. A sewing machine having stitching mechanism and a cross thread carrier movable in a continuous path in one direction, operating means for said carrier comprising a rotary shaft connected therewith, a driving shaft connected with said rotary shaft, a presser foot, and a hollow supporting bar therefor, said carrier shaft being located within said presser foot bar.
- 60 71. A sewing machine having stitching mechanism and looper mechanism cooperating therewith, a cross thread carrier movable in a continuous direction, and means

for causing said carrier to carry the thread during a part only of its travel.

72. In a sewing machine the combination of needle mechanism, looper mechanism, 5 and cross thread mechanism, the latter movable in a continuous substantially circular direction, and means for causing the cross thread mechanism to carry the thread during a part only of its movement.

10 73. A sewing machine having a presser foot, a hollow presser foot bar for supporting the same and a main driving shaft, in combination with needle mechanism, looper mechanism, and rotary cross thread mechanism 15 movable in a continuous direction, a shaft carried by said presser foot bar, means connecting said shaft with the main drive

shaft, and means connecting said shaft with said cross thread mechanism.

74. In a sewing machine the combination 20 of needle mechanism, looper mechanism, cross thread carrying mechanism movable in a continuous direction to engage and disengage the thread, means for conducting the thread thereto, a driving shaft, a shaft 25 transverse to said driving shaft connected therewith, and means connecting said transverse shaft with the cross thread carrying mechanism for imparting a continuous rotary movement thereto.

Signed at Nyack, New York, this 26th day of March, 1921.

JOHN P. WEIS.
